UNITED STATES PATENT OFFICE.

HARRY W. JONES, OF NEW YORK, N. Y., ASSIGNOR TO AMERICAN CAN COMPANY, OF NEW YORK, N. Y., A CORPORATION OF NEW JERSEY.

COMPARTMENT FRICTION-TOP CAN.

No. 906,236.

Specification of Letters Patent.

Patented Dec. 8, 1908.

Application filed August 19, 1907. Serial No. 389,158.

To all whom it may concern:

Be it known that I, HARRY W. JONES, a citizen of the United States, residing at New York, in the county of New York and State 5 of New York, have invented a new and useful Improvement in Compartment Friction-Top Cans, of which the following is a specification.

My invention relates to improvements in 10 compartment friction top cans.

The object of my invention is to provide a sectional or compartment can of a simple, efficient and durable construction, in which the closures for both sections or compartments will be between the two sections or compartments, so that both the upper and lower heads or ends of the vessel, as an entirety, may be smooth and plain and free from cap or cover-like projections, and so 15 that both closures may be protected or inclosed or embraced by the two sections or compartments of the structure as a whole, and in which the closure for the main or lower section may serve as the means for securing the two sections of the can together. 20

My improved can is especially designed for paints having bronze or other powder intended to be mixed with the liquid paint shortly before using, and which it is desired should 25 be kept dry and in a separate compartment from the liquid paint.

My invention consists in the novel construction of parts and devices and in the novel combinations of parts and devices 35 herein shown and described and by which this object or result is accomplished, the same being more particularly specified in the claims.

In the accompanying drawing forming a 40 part of this specification, Figure 1 is a central vertical section of a sectional or compartment can embodying my invention; Fig. 2 is a detail bottom view of the upper section showing a gasket or packing and the retaining flange therefor, partly broken away, and 45 Fig. 3 is a detail top or plan view of the lower or main section. Figs. 4 and 5 are sectional views illustrating modifications.

In the drawing, A represents the body of 50 the lower or main section, the same having preferably a lock or other side seam a, B the annular head disk of said lower section, soldered or otherwise united to the body A, and having a depending annular friction seat wall 55 b and preferably also a raised annular bead

b¹, and C is the bottom head of the lower or main section.

D is the body of the upper or horizontal section, the same being preferably seamless and having an integral head d and an integral outwardly projecting marginal flange or rim d¹. 60

F is the annular head disk of the upper or supplemental section, the same having an inner inwardly projecting annular friction 65 seat wall f surrounding its filling opening F¹ for engagement with the friction seat wall g of its friction cap or cover G, and also an outer annular friction seat wall f¹ for engagement with the friction seat wall b of the annular head disk B of the main section. The annular head disk F of the supplemental section D also has an outwardly projecting rim f² provided with a curved marginal flange f³, which embraces the packing or gasket H, 75 which is interposed between the annular head disk of the lower or main section and the annular head disk of the upper or supplemental section of the can. 70

The annular head disk F of the upper or 80 supplemental section is preferably secured to the body D of said section by solder d² between the rim d¹ of said section and the rim f² of said annular head disk F. The rim f² of the annular head disk F may preferably 85 be provided with an annular groove f⁴ to aid in retaining the packing or gasket H in place in the annular head disk F. The crease f⁵ between the packing holding flange f⁶ of the annular head disk F of the upper section 90 and the annular head disk B of the lower section, affords easy entrance to a wedge-like implement in prying off the upper section and thus opening the lower section. The annular head disk F of the upper or supplemental section serves as a friction cover 95 closure for the lower or main section and also as the means for locking or securing the two sections together.

In my invention, it will thus be seen that 100 both the main or lower section and the upper or supplemental section have annular head disks, and one of these annular head disks, that which is permanently secured to the upper or supplemental section is furnished with both an inner friction seat wall and an outer friction seat wall. The annular head disk B of the lower section has a single friction seat wall b, while the annular head disk F of the upper or supplemental 105 110

section has two friction seat walls, an inner one f , which receives the cap G , and an outer one f^1 which fits within the depending friction seat wall b of the annular head disk B of the lower or main section. This construction gives the complete structure both a smooth and permanently closed lower end or head C and a smooth and permanently closed upper end or head d , and the friction closures for both sections are at the meeting ends of the two sections and one within the other; so that both closures are protected by the main portions of the two sections and so that the closures are one within the other so that any accidental leakage from one compartment is not liable to get onto the outside of the combined can and thus discolor the other goods on the shelf. The annular head disks of the two sections being at the meeting ends of the two sections are thus brought into tight, firm and bracing contact with each other both at their interengaging annular friction seat walls b ; f^1 , and also at their rim or disk portions surrounding and outside of these friction seat walls indirectly through the interposed packing disk H . The double surfaces of contact at right angles to each other between the head disks of the two sections produce a very strong and secure union between the two so that one section is not liable to be tilted in respect to the other and the closure of the main section thus loosened.

When the upper and lower sections are secured together, the closures for both sections are between the two sections and protected and inclosed thereby; and both the upper and lower ends of the united or complete can as a whole are plain and smooth and free from external cap or closure-like projections. My improved can thus presents as an entirety a convenient form and shape for handling and shipment as the opposite flat ends of the can may be readily stacked or piled one on top of another.

45 The interior friction cap or cover G of the upper or supplemental section D has the customary marginal pry-off rim g^1 furnished with a fold g^2 .

In the modification illustrated in Figs. 4 and 5 the annular head disk F of the upper section is provided with a rim f^6 having an upturned flange f^7 which is folded over the rim or flange d^1 of the upper section D , thus securing these parts together.

55 In the modification illustrated in Fig. 5 the annular head disk F of the upper section, has a screw threaded flange f^8 surrounding its filling opening which is closed by a screw cap G^1 .

60 In the modifications illustrated in Figs. 4 and 5 a flat annular packing disk H is placed on the annular head disk F of the upper or supplemental section D surrounding the neck or friction seat wall portion f^1 thereof, and is securely held and clamped in position

when the two sections are forced snugly together and the friction seat walls b ; f^1 thus caused to have a firm, tight, frictional grip, one on the other.

In the modification illustrated in Fig. 5 a flat packing disk G^2 is interposed between the screw cap G^1 and the screw threaded flange f^8 .

I claim:—

1. A sectional or compartment can, comprising a main section having a body and an annular head disk secured to said body and provided with a depending friction seat wall at its inner edge, and a supplemental section having a body and an annular head disk secured to said body and furnished with both inner and outer friction seat walls, said outer friction seat wall closing the opening in the annular head disk of the main section, and said inner friction seat wall being upwardly projecting and receiving and having a friction cover closing the opening in the annular head disk of said supplemental section, said annular head disks of the two sections having bracing contact with each other both at their interengaging annular friction seat walls and also at their rim portions to securely unite the sections, substantially as specified.

2. A sectional or compartment can, comprising a main section having a body and an annular head disk secured to said body and provided with a depending friction seat wall at its inner edge, and a supplemental section having a body and an annular head disk secured to said body and furnished with both inner and outer friction seat walls, said outer friction seat wall closing the opening in the annular head disk of the main section, and said inner friction seat wall being upwardly projecting and receiving and having a friction cover closing the opening in the annular head disk of said supplemental section, and a packing interposed between said annular head disk of the main section and the rim portion of the annular head disk of the supplemental section, substantially as specified.

3. A sectional or compartment can, comprising a main section having a body and an annular head disk secured to said body and provided with a depending friction seat wall at its inner edge, and a supplemental section having a body and an annular head disk secured to said body and furnished with both inner and outer friction seat walls, said outer friction seat wall closing the opening in the annular head disk of the main section, and said inner friction seat wall being upwardly projecting and receiving and having a friction cover closing the opening in the annular head disk of said supplemental section, and a packing interposed between said annular head disk of the main section and the rim portion of the annular head disk of the supplemental section, said rim portion of said

annular head disk of the supplemental section having a marginal flange engaging said packing, substantially as specified.

4. A sectional or compartment can comprising a main section having a body, a permanently closed lower end and an annular head disk secured to said body at its upper end and a supplemental section having a body with a permanently closed upper end 10 and an annular head disk at its lower end, said annular head disks of the two sections being at the meeting ends thereof, and provided with interengaging annular friction seat walls and the annular head disk of one section having also a further annular friction seat wall, and said annular head disks of the two sections having also bracing engagement with each other at their rims, substantially as specified.

20 5. A sectional or compartment can, comprising a main section having a permanently closed lower end and a supplemental section having a permanently closed upper end, both said sections having annular head disks at 25 their meeting ends, the annular head disk of the one section serving as the closure for the annular head of the other section and provided with a filling opening having a closure, said closures for both sections being at the 30 meeting ends thereof, said annular head disks of the two sections having bracing contact with each other both at their interengaging annular friction seat walls and also at their rim portions to securely unite the sections, substantially as specified.

6. A sectional or compartment can, comprising main and supplemental sections, each having annular head disks, the annular head disk of one section having two friction seat 40 walls and serving as a closure for the other, and provided with a closure cap for its own opening, said closures for both sections being at the meeting ends of the two sections and the outer end of each section being permanently closed, 45 said annular head disks of the two sections having bracing contact with each other both at their interengaging annular friction seat walls, and also at their rim portions to securely unite the sections, substantially as specified.

50 7. A sectional or compartment can, comprising main and supplemental sections, each having annular heads, the annular head of one section serving as a closure for the other and provided with a closure cap for its opening, and a packing interposed between said annular heads of the two sections, said closures for both sections being at the meeting ends of the two sections and the outer end of each section being permanently closed, substantially as specified.

60 8. In a sectional or compartment can, the combination with the main section having an annular head disk, of a supplemental section 65 having an annular head disk closing the

opening in the annular head disk of the main section, and a cap closing the opening in the annular head disk of the supplemental section, said closures for both sections being at the meeting ends of the two sections and the 70 outer end of each section being permanently closed, said annular head disks of the two sections having bracing contact with each other both at their interengaging friction seat walls and also at their rim portions to 75 securely unite the sections, substantially as specified.

9. In a sectional or compartment can, the combination with the main section having an annular head disk, of a supplemental section 80 having an annular head disk closing the opening in the annular head disk of the main section, a cap closing the opening in the annular head disk of the supplemental section, and said supplemental section having a rim 85 to which its annular head disk is secured, said closures for both sections being at the meeting ends of the two sections, and the outer end of each section being permanently closed, said annular head disks of the two 90 sections having bracing contact with each other both at their interengaging annular friction seat walls and also at their rim portions to securely unite the sections, substantially as specified.

95 10. In a sectional or compartment can, the combination with the main section having an annular head disk, of a supplemental section having an annular head disk closing the opening in said annular head disk of the 100 main section, a cap closing the opening in the annular head disk of said supplemental section, and a packing interposed between the annular head disks of the two sections, said closures for both sections being at the meeting ends of the two sections and the outer end of each section being permanently closed, substantially as specified.

11. In a sectional or compartment can, the combination with the main section having an annular head disk, of a supplemental section having an annular head disk closing the opening in the annular head disk of the main section, a cap closing the opening in the annular head disk of the supplemental section and a packing interposed between the annular head disks of the two sections, the annular head disk of the supplemental section having a marginal flange engaging said packing, said closures for both sections being at the meeting ends of the two sections and the outer end of each section being permanently closed, substantially as specified.

115 12. In a sectional or compartment can, the combination with the main section having an annular head disk, of a supplemental section having an annular head disk closing the opening in the annular head disk of the main section, a cap closing the opening in the annular head disk of the supplemental sec- 120 125 130

tion and a packing interposed between the annular head disks of the two sections, the annular head disk of the main section having an annular raised bead, said closures for both sections being at the meeting ends of the two sections and the outer end of each section being permanently closed, substantially as specified.

13. In a sectional or compartment can, 10 the combination with a main section having an annular head disk B furnished with a friction seat wall b, of a supplemental section D having an annular head disk F furnished with an inner friction seat wall f and an outer 15 friction seat wall f^1 and a rim portion f^2 , said closures for both sections being at the meeting ends of the two sections and the outer end of each section being permanently closed, said annular head disks of the two sections 20 having bracing contact with each other both at their interengaging annular friction seat walls and also at their rim portions to securely unite the sections, substantially as specified.

14. In a sectional or compartment can, 25 the combination with a main section having an annular head disk B furnished with a friction seat wall b, of a supplemental section D having an annular head disk F furnished with an inner friction seat wall f and an outer 30 friction seat wall f^1 , a rim portion f^2 , and a cover G having a friction seat wall g, said closures for both sections being at the meeting ends of the two sections and the outer end of 35 each section being permanently closed, said

annular head disks of the two sections having bracing contact with each other both at their interengaging annular friction seat walls and also at their rim portions to securely unite the sections, substantially as specified.

15. In a sectional or compartment can, 40 the combination with a main section having an annular head disk B furnished with a friction seat wall b, of a supplemental section D having an inner friction seat wall f and an outer 45 friction seat wall f^1 , a rim portion f^2 , a cover G having a friction seat wall g and a packing H, said closures for both sections being at the meeting ends of the two sections and the outer end of each section being permanently closed, substantially as specified.

16. In a sectional or compartment can, 50 the combination with a main section having an annular head disk B furnished with a friction seat wall b, of a supplemental section D having an annular head disk F furnished with an inner friction seat wall f and an outer 55 friction seat wall f^1 , a rim portion f^2 , a cover G having a friction seat wall g, a packing H, 60 said annular head F having a retaining flange f^3 for said packing, said closures for both sections being at the meeting ends of the two sections and the outer end of each section being permanently closed, substantially as 65 specified.

HARRY W. JONES.
